US00D964458S

(12) United States Design Patent (10) Patent No.: US D964,458 S
Barlier et al. (45) Date of Patent: * Sep. 20, 2022

(54) TYPE FONT

(71) Applicant: Apple Inc., Cupertino, CA (US)

(72) Inventors: Guillaume P. Barlier, San Mateo, CA (US); Lisa K. Forssell, Palo Alto, CA (US); Joseph D. Gardner, San Francisco, CA (US); Aurelio Guzmán, San Jose, CA (US); Jason D. Rickwald, Santa Cruz, CA (US); Christopher J. Romney, San Francisco, CA (US); Nicolas V. Scapell, Sunnyvale, CA (US); Christopher I. Wilson, San Francisco, CA (US); Giancarlo Yerkes, Menlo Park, CA (US)

(73) Assignee: Apple Inc., Cupertino, CA (US)

() Term: 15 Years

(21) Appl. No.: 29/707,733

(22) Filed: Sep. 30, 2019

(51) LOC (13) Cl. 18-03

(52) U.S. Cl.

USPC D18/27

(58) Field of Classification Search

USPC D18/24, 28, 25, 27, 32, 33
CPC G09B 11/00; G09B 11/04; G09B 17/00;
B41B 1/02

(57) CLAIM

The ornamental design for a type font, as shown and described.

DESCRIPTION

The file of this patent contains at least one drawing/photograph executed in color. Copies of this patent with color drawing(s)/photograph(s) will be provided by the Office upon request and payment of the necessary fee.

FIGS. 1-29 are a face view of a type font showing the claimed design; and,

FIGS. 30-58 are another embodiment thereof.

1 Claim, 58 Drawing Sheets
(29 of 58 Drawing Sheet(s) Filed in Color)
